UNITED STATES PATENT OFFICE.

CLARENCE A. HAMMOND-KNOWLTON, OF NEW YORK, N. Y.

THREAD-HOLDER.

1,171,194.

Specification of Letters Patent. Patented Feb. 8, 1916.

Application filed May 12, 1915. Serial No. 27,597.

To all whom it may concern:

Be it known that I, CLARENCE A. HAMMOND-KNOWLTON, a citizen of the United States, and a resident of the city of New York, borough of Manhattan, in the county and State of New York, have invented a new and Improved Thread-Holder, of which the following is a full, clear, and exact description.

10 This invention relates to thread holding devices and has for an object the provision of an improved combined holder and cover which, before the same is opened, protects the thread against dust and when opened exposes only a small part of the thread while holding the same in proper position for ready access.

20 Another object in view is to provide a combined holder and wrapper for skeins which will thoroughly protect the thread before the wrapper is broken and will act as a protecting holder after the wrapper has been broken.

25 A still further object of the invention is to provide a combined wrapper and holder formed from a single blank and cut and creased so as to be readily folded after the skein has been placed in position thereon and finally sealed.

30 In the accompanying drawings:—Figure 1 is a plan view of the blank as the same is first cut out; Fig. 2 is a view similar to Fig. 1 except that the hank has been placed thereon; Fig. 3 is a plan view showing the

35 next step in folding the wrapper around the hank; Fig. 4 is a detail perspective view showing a reinforcing member for holding one end of the hank in place; Fig. 5 is a view similar to Fig. 3 except that the hank

40 and part of the wrapper connected therewith have been folded over against the outer edge of the wrapper; Fig. 6 is a view similar to Fig. 5 but showing the sealing flap folded over the body of the wrapper; Fig. 7 is a fragmentary view of the upper end of the holder and wrapper with the sealing upper section folded over the body of the holder; Fig. 8 is a view similar to Fig. 7 but with the sealing end wrapped completely

45 around the upper end of the body of the holder; Fig. 9 is a front view of the entire holder in its completely folded condition with the sealing strip arranged thereon; Fig. 10 is a rear view of the structure shown

50 in Fig. 9; Fig. 11 is a view similar to the upper part of Fig. 10 except that the per-

forated section has been removed so as to secure access to the thread; Fig. 12 is a view similar to Fig. 11 but showing the next step in opening the sealing cap, the view being 60 taken from the opposite side to that shown in Fig. 11; Fig. 13 is a view similar to Fig. 12 but with the sealing flap unfolded and partly torn away; Fig. 14 is a sectional view through Fig. 13 on line 14—14; Fig. 15 65 is a view similar to Fig. 13 but looking at the holder from the opposite side; Fig. 16 is a view similar to Fig. 15 except that the cap has been entirely torn away.

Referring to the accompanying drawings 70 by numerals, 1 indicates the blank in its entirety, which is clearly shown in Fig. 1. The blank is provided with what may be termed a body 2 which in turn is marked off into different sections 3, 4 and 5, section 3 75 acting as a thread holder *per se*, while sections 4 and 5 act as covering members. The thread holding member 3 is provided with a notch 6 at one end and at the opposite end with a slit 7 together with a projection or 80 flap 8, said projection or flap being notched at 9 and 10 so that when folded over and tucked through the slit 7 a notch the same as notch 6 will be provided, as shown in Fig. 2.

At the end of the blank carrying the slit 85 7 the sections 4 and 5 are provided with sealing flaps 11 and 12, while section 5 is provided on the side with a sealing flap 13. Adjacent the end of the blank opposite the slit 7 is arranged a line 14 which may be 90 scoring, perforation or crease, as desired. This line is intended to act as a tearing line so that all of the part of the blank extending therebeyond may be removed, as shown in Fig. 16, when the thread is to be used. 95 The part beyond the line 14 may be termed, broadly, a cap which is folded by successive steps, as shown in Figs. 2 to 8, inclusive.

The blank is cut at lines 15, 16 and 17 100 whereby a block or section 18 is provided which may be torn off immediately previous to the placing of the thread 19 in place on the holder 3, as shown in Fig. 2. The block 18 is torn off and folded so as to act as an abutment or bearing member when thrust beneath the flap 8, as shown in Fig. 4. After the block 18 has been positioned as shown in Fig. 4 the thread 19 is then placed on the holder, the holder being bowed somewhat so as to allow this action, and then allowed to 105 straighten so that the same will appear as shown in Fig. 2. After the thread has been

arranged in position in this manner the holder 3 is turned over to the position shown in Fig. 3 and then turned a second time to the position shown in Fig. 5, whereby the sections 4 and 5 will be arranged on opposite sides of the holder 3 and properly cover the thread. The flap 13 is then folded over, as shown in Fig. 7, after which the end flap 12 is folded over as shown in Fig. 6 and sealed by having an eyelet 20 placed therethrough and also through the remaining folded parts. Before moving the thread from the position shown in Fig. 3 to that shown in Fig. 5, the flap 11 is folded up, as clearly shown in Fig. 3, so that the flaps 11 and 12 will thoroughly protect that end of the thread. The eyelet 20 is desirable not only as a seal but as a bearing for hanging or holding the thread against the pull while in use. This enables the user to take strands of thread from the package with one hand only.

When the parts are all arranged as shown in Fig. 6, the folding of the wrapper is complete and the next operation is the folding of the cap 22, which cap is provided with a body 23 (Fig. 1) including part of the flap 13 and a folding strip 24. The folding strip 24 is bent over from the position shown in Fig. 6 to that shown in Fig. 7, whereby the block 25 will cover the upper end of the flap 13 and the upper end of the section 5. The remaining part of the strip 24 is then wrapped around the holder 3 and section 4 until the parts assume the position shown in Figs. 9 and 10. Afterward the sealing strip 21 is placed in position. Usually there is no adhesive used upon the blank 1 shown in Fig. 1 as these parts are held together by the sealing strip 21 and also by the eyelet 20, though adhesive could be used without departing from the invention. The folding strip 24 is provided with the perforated lines 26 in the block or section 27 so that the material between these lines may be torn out, as shown in Fig. 11, when the cap is to be removed.

Before describing the removal of the cap it is pointed out that the thread within the holder is completely inclosed by a substantially dust-proof and light-proof holder or casing. In order that the thread may be readily used, at least one end must be exposed, and in order to properly do this a perforated line 14 (Fig. 1) is provided so that the cap may be torn off entirely, leaving a short portion of the holder 3 projecting, as shown in Fig. 16, thus exposing a sufficient amount of the thread to be readily grasped in drawing any desired amount from the holder.

From Figs. 11 to 16, inclusive, will be seen various stages of the removal of the cap 22. In Fig. 11 the material between lines 26 has been torn and moved upwardly

out of the way. Fig. 12 is a somewhat similar view to Fig. 11 but the portions 28 and 29 of strip 24 have been spread so as to form extensions or wings of the block 25. The body or block 23 (Fig. 1) is then grasped by the hand and torn off, the tearing including the upper part of the flap 13. Afterward the sealing strip 21 is broken, whereupon the cap is entirely disconnected and may be readily removed, which will result in a structure as shown in Fig. 16.

What I claim is:—

1. In a skein holder, a thread supporting body, covering sections arranged adjacent said body and adapted to be folded thereover, an end flap arranged on each of the covering sections adapted to fold over the end of said body so as to cover the thread carried thereby, a cap extending from one of the covering sections, said cap being formed with a plurality of folds or creases and then wound around the upper end of said body, and means for holding said cap against unwinding.

2. A skein holder formed from a single blank provided with a thread holding body, a pair of covering sections formed with a flap at one end of each section and a side flap on one of the sections, and means extending from one of the sections defining a cap, said means comprising a plurality of blocks adapted to be folded over and around one end of said body.

3. In a skein holder of the character described, a thread holding body formed with a notch at the upper end, a slot and a tab at the lower end, said tab adapted to have one end thrust through the slot so as to form a closed loop, a thread backing member or abutment fitting into said loop, a pair of covering sections arranged on one side of said body and adapted to be folded over the body, each of said sections being formed with an end flap adapted to be folded over the end of said body when the sections are folded over the body, a side flap for the outer of said covering sections, and a cap structure connected with said outer covering section, said cap structure being formed with a block extending from said last mentioned section to the upper end of said body so as to cover one side of the end of said body, a second block adapted to be folded over and cover the opposite side of said body, an extension on said second block adapted to be folded around the upper end of said body, said extension being formed with a removable perforated section, and means for holding said cap in its folded position.

4. In a thread holder of the character described, a body for receiving thread, a pair of sections adapted to be wrapped around said body for covering the same with the exception of one end, and a cap connect-

ed with one of said sections adapted to be folded over and wrapped around the exposed end of said body, whereby the thread is completely inclosed.

5 5. In a thread holder of the character described, a body, a reinforcing member arranged adjacent one end of said body, a foldable locking tab for holding said reinforcing member in position, means for inclosing said body and said reinforcing member together with thread mounted on the body, and a cap extending from said means, said cap being formed with a foldable section and a projection extending therefrom 10 adapted to be wound around the end of said body so as to produce an inclosing cap therefor.

15 6. A thread holder formed from a single blank cut so as to present a thread holding body, a pair of inclosing sections, a cap structure, and overlapping flaps at the end opposite the cap structure.

20 7. A thread package comprising a skein holding body, an inclosing cover therefor, 25 means for connecting the skein holding body to the cover at one end, and a removable

integrally formed cap at the opposite end of the cover, and a breakable joint between the cover and the cap.

8. A thread package comprising a skein 30 holding body and an inclosing cover therefor, means for connecting the skein holding body to the cover at one end the cover provided with a removable end or cap at its opposite end and when removed exposing 35 one end of the skein holding body and the skein.

9. A thread package comprising a skein holding body and an inclosing cover therefor entirely inclosing the skein and skein 40 holding body, and a frangible joint in the cover near the end whereby one end of the cover may be removed to expose the end of the skein holding body and skein.

In testimony whereof I have signed my 45 name to this specification in the presence of two subscribing witnesses.
